UNITED STATES PATENT OFFICE.

ROBERT WILLIAM BRUMBY AND SIMPSON CLARKE, OF HULL, ENGLAND.

DESIGN FOR A CALENDAR-CASE.

SPECIFICATION forming part of Design No. 22,299, dated March 14, 1893.

Application filed November 10, 1892. Serial No. 451,591. Term of patent 7 years. Patented in England, No. 187,364, Class I, February 6, 1892, and No. 186,983, Class III, January 28, 1893.

To all whom it may concern:

Be it known that we, ROBERT WILLIAM BRUMBY and SIMPSON CLARKE, citizens of Great Britain, residing at Hull, in the county of York, England, have invented and produced a new and original Design for Calendars, (which has been patented to us in Great Britain, No. 187,364, Class I, February 6, 1892, and No. 186,983, Class III, January 28, 1892,) of which the following is a specification, reference being had to the accompanying drawing forming part thereof.

The figure is a perspective view of our newly designed calendar which is the only view deemed to be necessary to fully illustrate our design.

Our design is for a calendar case and we give it the conventionalized form of a pump. The casing *a* and the ridged roof *v* are de-

signed to represent planks. The edges of *a* 20 casing *a* are represented as being bound with iron bands *c*. A pump handle *d* is represented as issuing from an aperture in the right side of the casing and a delivery spout *e* from the front of said casing. At the lower front side 25 of said casing under said spout is represented a water trough *i* and half way up said front of the casing a broken edged aperture *f*.

Having thus described our design, what we claim, and desire to secure by Letters Patent, 30 is—

The design for a calendar case as herein described and shown.

ROBERT WILLIAM BRUMBY.
SIMPSON CLARKE.
